UNITED STATES PATENT OFFICE.

HENRY KREISINGER, OF PITTSBURGH, PENNSYLVANIA, AND JOHN ANDERSON, OF MILWAUKEE, WISCONSIN, ASSIGNEES TO COMBUSTION ENGINEERING CORPORATION, A CORPORATION OF NEW YORK.

METHOD OF AND APPARATUS FOR BURNING PULVERIZED FUEL.

Application filed April 26, 1922, Serial No. 556,566.

This invention relates to a method of and apparatus for burning pulverized fuel and one of the primary objects of our invention is to promote more perfect and rapid combustion and to increase efficiency. Another object is to burn more fuel in less time in a furnace of given size; or to increase the capacity of an existing furnace of given size.

The foregoing, together with such other objects as may hereinafter appear, or are incident to our invention, we obtain by means of a method and apparatus, illustrated in preferred form in the accompanying drawings in connection with a steam generating boiler, for which purpose our invention is particularly useful.

Of the drawings, Fig. 1 is a longitudinal vertical section through a furnace embodying our improvements; Fig. 2 is a section taken on the line 2—2 of Fig. 1; Figs. 3 and 4 are enlarged sectional views of the burner mechanism used in carrying out our invention, Fig. 4 being a section taken on the line 4—4 of Fig. 3; Fig. 5 illustrates a modification of our invention partly in section and partly in plan; and Fig. 6 is a partially sectional and plan view illustrating still another modification of our invention.

Referring now particularly to Figs. 1 and 2, it will be seen that the combustion chamber A of the furnace is substantially rectangular in cross section, and has considerable horizontal length and vertical depth. The horizontal depth is less than the length and may be less than the vertical depth. At the top, the combustion chamber is provided with an outlet 7, over which are located the evaporating surfaces of the boiler, such, for example, as the banks of tubes 8. The combustion chamber is of such size that combustion is completed therein in the manner hereinafter described, and the hot gases are baffled through the tubes 8 in any desired manner and finally conducted to the flue 9 leading to the stack, (not shown) creating the draft.

In the top wall 10 of the combustion chamber we arrange a row of burners B, the construction of which will be hereinafter more fully described. These burners deliver the fuel in a downward direction, adjacent the front wall 11 through which preferably a large

portion of the air needed for combustion is supplied through means of the rows of openings 12. There are a plurality of openings 55 in each row, and the openings of one row are preferably staggered with respect to the openings of the adjacent row or rows; all of the openings constituting a battery through which air is induced by the natural draft of 60 the stack. It will be noted that the lowest row of openings is well toward the bottom of the combustion chamber. The fuel is preferably mixed with sufficient air to act as 65 "carrying" air, and the mixture is preferably delivered at a velocity such that the draft will turn the fuel and flame stream above the bottom of the combustion chamber.

Referring now to Figs. 1, 3 and 4, the fuel, or a mixture of the fuel and air is delivered 70 to each burner by means of a pipe 14, such pipe discharging into a burner nozzle 15. This member may be termed a fish-tail burner nozzle because of its shape. It is designed to deliver the fuel, or a mixture thereof with 75 air, into the combustion chamber in the form of a thin sheet 16. The discharging sheet of fuel is surrounded by air which is drawn through the burner casing 17 by induction. The amount of air thus drawn through the 80 burner casing directly around the sheet is controlled by the dampers 18, which may be varied as conditions demand. The interior of the casing 17 is divided by a wall or septum 19 providing a channel 20 on the inside of the burner, that is the side toward the outlet 7. A body of air is also drawn through this channel 20, the momentum of this body of air being capable of variation, through proper manipulation and adjustment of the 85 dampers 18 and the main damper 21. The momentum of this body of air exerts a considerable influence as to the point at which the fuel and flame stream is turned, the greater the momentum, the farther down the point 90 of turning. Thus the level of the bottom of the fuel and flame stream may be altered. Furthermore, the air drawn in through the channel 20 supplies the space between the descending and ascending portions of the fuel and flame stream, thereby supplying oxygen 95 for combustion at such point most effectively. This is of importance for the individual entering streams later unite in a single stream

as gasification and expansion take place. In this connection the ascending portions may be considered as a single body or stream.

Of the air which is drawn through the 5 battery of openings 12 in the front wall 11, a portion finds its way to the spaces between the sheets as they leave the burners and from thence into the space between downward and ascending portions of the fuel and flame 10 streams; a portion is mixed with the fuel and flame as gasification begins with consequent expansion and setting up of eddies; and a portion follows the natural stream line course of the fuel and flame stream, bordering such 15 stream and providing a body of air into which the heavier unconsumed or partially consumed particles which gravitate find the needed oxygen for completion of combustion. It will be seen from the foregoing that 20 many more burners may be employed when they are disposed in the manner described, and that each burner may be constructed to carry a relatively or comparatively small quantity of fuel, so that the entering fuel 25 is split up into a number of thin sheets as a result of which it is possible to secure the greatest degree of exposure of the fuel particles to air. In this connection it will be seen that the greatest opportunity is presented 30 for the enveloping of each particle of fuel with a body of air, notwithstanding which the aggregate amount of fuel which may be admitted may be considerably increased over the amount possible in other practices. The 35 auxiliary air is successively supplied through the inlets 12 to meet requirements as combustion proceeds and the air induced travels at less velocity than the incoming fuel setting up eddying. In consequence of the foregoing, ignition takes place more quickly and combustion is completed more rapidly.

Incombustibles or refuse matter not carried out through the stack, gravitate to the bottom in the form of a flocculent ash, the 45 deposit being cooled by the water screen located in the bottom portion of the combustion chamber and consisting of pipes 22 and 23 connected into the circulation of the boiler. Any desired number of such pipes may be employed. Their function is to absorb the 50 radiant heat from the deposit and maintain the temperature thereof below the point at which coalescing or substantial fusion takes place. The ash may, therefore, be readily removed through the ash door 24. and continuous operation of the furnace had without 55 shutting down for the removal of slag.

The walls of the combustion chamber are 60 cut back as indicated at 25 to provide re-entrant portions. The slag which forms on the vertical walls in dripping down from the overhanging portions is cooled by the screen and the drippings remain in the form of more or less small nodules, readily capable of 65 removal with the ash.

The openings 12 are damper controlled, as indicated in Fig. 1.

In the modification shown in Fig. 5, the combustion chamber A' is practically square in cross section and burners are arranged on 70 opposite sides of the centrally located discharge outlet 7'. The burners, it will be observed, are arranged in staggered relation, and there are fewer burners to a row than would be the case where firing but from one 75 side of the furnace is employed, as in the construction of Figs. 1 and 2. By this arrangement opportunity is provided for the sheets to, as it were, interlace as they expand and are turned in toward each other. Thus with 80 two sided burning proper air supply may be had with a minimum horizontal depth of combustion chamber.

In the modification shown in Fig. 6, a two sided burning arrangement is shown, but 85 in this case the burners of one row are opposite, or more properly speaking, in alignment with the burners of the opposite row. With such arrangement the combustion should have greater horizontal depth as in- 90 dicated.

It will be seen that in each form we obtain the advantage of being able to admit a maximum quantity of fuel in such manner as to 95 secure maximum exposure to enveloping air, with quicker ignition and more rapid combustion, and this in a combustion chamber of minimum size.

What we claim is:

1. In pulverized fuel burning apparatus, 100 the combination of a furnace having an outlet, and a row of burners on each of two opposite sides thereof, said burners being constructed to each deliver fuel in the form of a sheet, the sheets of each row presenting their 105 sides toward each other, and the sheets of each row being adjacent one another.

2. In pulverized fuel burning apparatus, 110 the combination of a furnace having an outlet, and a row of burners on each of two opposite sides thereof, said burners being constructed to each deliver fuel in the form of a sheet, the sheets of each row presenting their 115 sides toward each other, and the sheets of one row being staggered with respect to those of the other row.

3. In apparatus for burning pulverized fuel, the combination, with a combustion chamber having walls and an offtake for the products of combustion located in an upper 120 part of the chamber, of a row of burners at the top of the chamber adjacent a wall removed from the offtake and directed downwardly, each burner having a pulverized fuel nozzle of elongated cross-section the longer dimension of which is in a plane substantially perpendicular to the plane of said wall, so that each stream of fuel in suspension bends on edge to take a U-shaped course to the offtake, and air admission means in said wall de- 125 130

livering air transversely of the flow of the legs of the U in a direction parallel with the planes of the sheets of fuel.

4. The method of burning pulverized fuel in a chamber having an offtake in an upper part, which consists in admitting the fuel downwardly from an upper portion of the chamber remote from the offtake in a plurality of substantially parallel sheet-like streams presenting their flat sides toward one another, in bending each fuel and flame stream

on its edge toward the offtake to take a U-shaped course through the chamber, in admitting air for combustion transversely of the legs of the U in a direction parallel with the planes of the sheets of fuel, in igniting the fuel, and in burning it in suspension within the chamber. 15

In testimony whereof, we have hereunto signed our names.

HENRY KREISINGER.
JOHN ANDERSON.
